US00D930026S

(12) **United States Design Patent** (10) Patent No.: **US D930,026 S**
 Asahioka (45) Date of Patent: ** Sep. 7, 2021

(54) **DISPLAY SCREEN WITH GRAPHICAL USER INTERFACE**

(71) Applicant: **FUJITSU GENERAL LIMITED**, Kawasaki (JP)

(72) Inventor: **Munehisa Asahioka**, Kawasaki (JP)

(73) Assignee: **FUJITSU GENERAL LIMITED**, Kawasaki (JP)

(**) Term: **15 Years**

(21) Appl. No.: **29/731,579**

(22) Filed: **Apr. 16, 2020**

(30) **Foreign Application Priority Data**

Dec. 13, 2019 (JP) 2019-027755

(51) **LOC (13) Cl.** **14-04**

(52) **U.S. Cl.**

USPC **D14/486**

(58) **Field of Classification Search**

USPC **D14/485-95**

(57) **CLAIM**

The ornamental design for a display screen with graphical user interface, as shown and described.

DESCRIPTION

The sole FIGURE is a front view of a display screen with graphical user interface showing my new design.

The broken lines showing the display screen form no part of the claimed design. The remaining broken lines showing text and graphic elements in the graphical user interface form no part of the claimed design.

1 Claim, 1 Drawing Sheet
